UNITED STATES PATENT OFFICE.

MILLARD M. BOWLUS, OF BOWLUSVILLE, OHIO.

TRACE-FASTENER.

SPECIFICATION forming part of Letters Patent No. 223,701, dated January 20, 1880.

Application filed November 26, 1879.

To all whom it may concern:

Be it known that I, MILLARD M. BOWLUS, of Bowlusville, in the county of Clarke and State of Ohio, have invented a new and Improved 5 Trace-Fastener, of which the following is a specification.

The object of my invention is to provide a safe, easily-operated, and strong device for fastening the ends of the traces to the single-tree.

10 The device consists of a flat metal spring attached to the back edge of the single-tree, and provided with a notch which receives the edge of the end of the trace, and, together with an adjacent notch in the single-tree, holds the 15 end of said trace on the single-tree.

In the accompanying drawings, Figure 1 is a top view of a single-tree provided with my improvement, and Fig. 2 is a rear edge view of the same.

20 Similar letters of reference indicate corresponding parts.

Referring to the drawings, A is the single-tree, on the ends B B whereof the traces are placed.

25 C is the trace-fastener. It is composed of a flat spring of brass or other suitable metal, having at its inner end, a, two projecting ears, b b. Near the opposite end, c, the flat metal spring is twisted at right angles to its edge 30 and formed into a curved notch, d.

The fastener thus formed is applied to the back edge e of the single-tree A, one fastener to each of the ends B B, and the said fasteners are attached to the single-tree by bending the 35 ears b b around the same, and by a screw, f, driven through a hole at the end a of the spring-fastener into the wood of the single-tree. That part of the fastener containing the

curved notch d projects above the top h of the single-tree, and the notch d is in line with a 40 notch, i, in the rear edge of the single-tree near each end. The bent end c of the fasteners beyond the notch d is for the finger to press against when the trace is attached.

The manner of operating the device is as 45 follows: The trace D, having a transverse slot in its end k, is slipped on one of the ends B of the single-tree. The finger is at the same time pressed against the end c, so as to force the spring-fastener back in the direction of the 50 arrow. The trace is then pushed up on the single-tree until it is in the notch i, when the finger is removed from the end c, whereby the spring-fastener springs back against the edge of the single-tree and the end k enters the 55 notch d, where it is held in the manner shown in the drawings.

The notches d i prevent the trace from slipping laterally, and the fastener C prevents, by the trace being held in the notch d, the trace 60 from slipping from the notch i in the single-tree.

I am aware that a spring has been pivoted to a single-tree and adapted to enter the eye of the trace-fastening; but 65

What I claim is—

A trace-fastener consisting of a flat spring having at one end the ears b, and having the ends c twisted to form a curved notch, in combination with a single-tree having the notch i, 70 as shown and described.

MILLARD M. BOWLUS.
